HENRY C. INGRAHAM, OF TECUMSEH, MICHIGAN.

Letters Patent No. 87,939, dated March 16, 1869.

IMPROVED HAND-TRUCK

The Schedule referred to in these Letters Patent and making part of the same.

To all whom it may concern:

Be it known that I, HENRY C. INGRAHAM, of Tecumseh, in the county of Lenawee, and State of Michigan, have invented a new and useful Improvement in Hand-Barrows; and I do hereby declare that the following is a full and complete description of the construction and operation of the same, reference being had to the accompanying drawings, making part of this specification, in which—

Figure 1 is a side view of the barrow as in use;

Figure 2 is a top view;

Figure 3 is a side view; and

Figure 4 is a view of a pipe resting upon its support, or table, in readiness to be removed.

The object of this invention is to provide means for removing undried drain-tile from the machine in which they are formed, without the hazardous necessity of handling them; and

It consists of a kind of adjustable barrow, by means of which the pipes can be removed to the place for drying, without danger of injury.

A represents the frame of the barrow, and

B represents the wheels, of which there are two.

C represents a bent axle, and

D, an arm upon each axle, extending at right angles thereto.

E is a connecting-rod, one end of which is connected, by a pivot-joint, to the arm D, and the other end of the connecting-rod E is united, by means of a pivot-joint, to the lever F, as shown in fig. 3.

The lever F is pivoted to the frame A at G, as shown in fig. 1.

H represents fingers or arms, that extend forward from the frame A, to which they are attached; and in the use of this machine, these fingers are thrust forward beneath the board upon which the newly-formed tile rests, the lever F being elevated, as shown in fig. 3, also shown by red lines in fig. 1.

Now, by depressing the lever F, as shown in fig. 1, the bent axle is partially rotated, and the wheels acting as a fulcrum, the fingers are elevated, and the pipe can thus be transported to the place for drying, and by again elevating the lever F, the load is deposited.

The axle-tree is secured to the frame A by means of two springs, I, one only being shown in fig. 1. By this means the barrow is prevented from sudden concussions, or jarring, as the newly-formed tile is being moved.

Having thus described my invention,

What I desire to secure by Letters Patent, is—

1. The bent axle C, connecting-rod E, and lever F, in combination with the frame A.

2. The spring I, in combination with the axle-tree C and frame A, as shown and described.

In testimony whereof, I have signed my name to this specification, in the presence of two subscribing witnesses.

Witnesses: HENRY C. INGRAHAM.

J. MCKENNEY,

Wm. A. MCKENNEY.
